UNITED STATES PATENT OFFICE.

JACOB MÜLLER, OF SIEGEN, GERMANY.

LOOSE LEAF TO BE USED WITH A CARBON FOR BOOKKEEPING MACHINES OR THE LIKE.

Application filed May 11, 1927, Serial No. 190,628, and in Germany January 24, 1927.

In bookkeeping machines or the like, it frequently happens that the carbon sheet to be used with a loose leaf successively receiving the single entries gets displaced or bent 5 over at its corners whereby the blank spaces at the sides of the leaf are soiled or the entries are incorrectly copied, while besides it is time-wasting and cumbersome to place the carbon sheet in its proper position on the 10 leaf and so introduce leaf and carbon sheet into the machine for each single entry to be made.

The present invention provides improved means by which the carbon sheet is securely 15 fastened in its proper position on the leaf before its introduction into the machine and not removed therefrom until the leaf has been completely filled-up.

The accompanying drawing illustrates the 20 improvement: Figs. 1 and 2 are plan views of the leaf, with and without the carbon sheet thereon, while Fig. 3 is an enlarged cross-section through the upper and lower ends of the leaf with the carbon sheet on the 25 line 3—3 of Fig. 2.

The leaf *a* is on both sides provided with blank longitudinal marginal spaces *b*, *c* and with holes *d* for the reception of file pins, the carbon sheet *f* of equal height to that 30 of said leaf and of a breadth required for the entries to be copied being fastened to said leaf before introducing it into the machine. To this end, the carbon sheet is at its upper and lower ends provided with inwardly 35 directed pockets *g* which can be fitted over that part *i* of the upper and lower ends of

the leaf *a* located between said blank spaces *b*, *c* and bounded by slots *h* in said ends of a depth corresponding to that of the pockets *g*. Said ends *i* are provided with a detaching line, for instance with small perforations *k* or the like, running over the whole breadth of the leaf *a* at a distance from the upper and lower edges of the latter corresponding to the depth of said slots *h*, for the 40 purpose of detaching said ends *i* from the leaf before filing the filled-up leaf in a binder or the like, so that said ends, or their slots *h*, do not form any impediments but the leaf has then uninterrupted upper and lower 45 edges.

What I claim, is:

The combination with a leaf for bookkeeping machines or the like, said leaf having blank longitudinal marginal spaces at 50 both sides thereof and that part of the upper and lower ends of the leaf located between said blank spaces being bounded by slots 55 therein, of a detaching line running over the whole breadth of the leaf at the upper and lower ends and at a distance from the upper and lower edges thereof corresponding to the depth of the slots therein, and a carbon sheet having inwardly directed pockets on its upper and lower edges and fastened 60 therewith on said leaf by its pockets embracing the slot-bounded part of the upper and lower ends of said leaf.

In testimony whereof I have hereunto set my hand.

JACOB MÜLLER.
